BUCKLE APPLYING MACHINE

George E. Klock and Kenneth J. Harwood,
Neenah, Wis., assignors to International Cellu-
cotton Products Company, Chicago, Ill., a cor-
poration of Delaware

Application April 13, 1939, Serial No. 267,735

8 Claims. (Cl. 223—49)

Our invention relates to apparatus for facilitating the attaching of slide buckles or the like to the straps, tape, or elastic with which those buckles are ordinarily used.

Heretofore most slide buckles have been attached by hand, and while this method is reasonably satisfactory for the larger size buckles, it is not fully satisfactory for small buckles such as are used on sanitary belts, the straps of women's lingerie, and the like. Not only are these buckles difficult to handle because of their size, but when supplied open, which is practically a necessity for hand attachment, they have a tendency to become entangled one with another, with the result that large amounts of time are expended in getting the buckles ready for use. The principal object of our invention, therefore, is to provide an automatic or semi-automatic machine for attaching slide buckles, particularly slide buckles of the smaller sizes, to the straps, tape, or elastic with which such buckles are used.

Other objects and the various advantages of our invention will be made more apparent by reference to the accompanying drawings and the following description of one preferred embodiment thereof. In the drawings—

Figure 1 is a side elevational view, partially in section, of a buckle-attaching machine in accordance with our invention;

Figure 2 is a perspective view of a slide buckle of the general type which the machine of our invention is particularly adapted to apply;

Figures 3, 4, and 5 are perspective views illustrating certain of the operations followed in applying buckles by the machine of our invention;

Figure 6 is a perspective view illustrating one convenient method of handling buckles of the general type illustrated in Figures 2 to 5;

Figure 7 is a front, elevational view, partially in section, on the line 1—1 of Figure 1;

Figures 8 and 9 are enlarged fragmentary sectional views illustrating the operation of the buckle feeding mechanism;

Figure 10 is a fragmentary perspective view illustrating the operating means for the buckle feeding mechanism;

Figure 11 is an enlarged sectional view on the line 11—11 of Figure 7;

Figure 12 is a sectional view taken on the general line 12—12 of Figure 11 and illustrating the operation of the buckle opening mechanism;

Figures 13 and 14 are fragmentary sectional views on the lines 13 and 14 of Figure 12;

Figure 15 is an enlarged perspective view illustrating the relative position of the buckle and

the strap or elastic to which it is to be attached immediately prior to the buckle closing operation;

Figure 16 is a fragmentary sectional view, generally similar to Figure 12, illustrating the operation of the buckle closing mechanism;

Figure 17 is a perspective view, partially in section, which illustrates particularly certain of the features of the buckle feeding and closing mechanisms; and

Figure 18 is a perspective view, partially in section, of the buckle supply magazine.

The buckle applying machine illustrated in the drawings includes a magazine for holding a supply of buckles, means for feeding buckles in sequence from the magazine to a working position, means for securely holding each buckle so fed at said working position, means for opening each buckle after it is moved to the working position to permit its being applied to the strap or elastic with which it is to be used, and means for then reclosing the buckle. The machine is particularly designed for applying slide buckles of the conventional type, that is, buckles having the general shape of a flattened figure eight as illustrated in Figure 2, and for reasons which will hereinafter appear, it is desirable that the central bar portion of the buckles supplied to the machine shall be split or at least deeply scored in order to facilitate the opening thereof.

The buckle magazine is illustrated particularly in Figures 17 and 18 and comprises an elongated, hollow body 19 which terminates at its lower end in an enlarged, square sided base 21 adapted to rest upon a U-shaped member 23 which serves as the frame of the buckle feeding mechanism, the frame 23 being rigidly attached as by welding to a metallic plate 25 which serves as the main frame of the machine. The magazine is removable as a unit, and to insure its proper positioning with respect to the other elements of the buckle feeding mechanism, the base portion 21 thereof is provided with suitable openings 27 (Figure 18) for engaging dowel pins 29 extending upwardly from the frame 23. The cross sectional dimensions of the central passageway 31 within the magazine are such that the edges of the buckles will engage the inner walls of the magazine with a sliding fit. To aid in accomplishing even feeding of the buckles from the magazine, a weight of suitable type, for example a cylindrical metal rod as illustrated at 33, may be placed within the passageway 31. The buckles are prevented from vertical movement out of the lower end of the magazine by

two oppositely arranged plate members 35 which are affixed to the bottom surface of the magazine base 21, as illustrated particularly in Figure 18.

In order to hold the magazine against movement during the operation of the feeding mechanism, the machine is provided with a bifurcated spring clip 37 which is rigidly attached to a rotatable shaft 39 extending between the side portions of the U-shaped support frame 41 for the buckle closing mechanism. The supporting shaft 39 for this clip 37 terminates in a crank 43, as illustrated in Figures 1 and 7, and a pivoted latching member 45 is provided for engaging this crank 43 to latch the clip 37 in the magazine supporting position of Figure 17. The clip 37 and its associated support and latching means constitute a convenient means for releasably holding the magazine in cooperative relation with the buckle feeding means. When it is necessary to refill or replace the magazine, all that need be done is to release the latch 45, rotate the clip supporting shaft 39 in a counterclockwise direction (Figure 17), and lift the magazine bodily out of the machine.

For convenience in loading the magazine, it is desirable that the buckles shall be supplied strung on a strip or cob of fiber 40, as illustrated in Figure 6. While still held on the fiber strip, the buckles are placed in proper position within the magazine, the end of the strip which projects from the bottom of the magazine is torn off, and the remainder of the strip is withdrawn from the top of the magazine, the buckles being held in the magazine by the inwardly projecting edges of the plates 35.

Buckles are fed in sequence from the lower end of the magazine to the working position (illustrated in Figures 11, 12, and 16) by means of a reciprocating plunger 47 which moves within a rectangularly shaped guideway 49 formed by the upstanding side of the U-shaped frame 23 of the feeding mechanism. The plunger 47 is held within the guideway 49 by a suitable removable plate 51. For convenience in operation, the buckle feeding mechanism is arranged to be actuated in response to sidewise movement of a downwardly extending lever 55 provided at its lower end with a pad 57 adapted to be engaged by the knee of the operator. This knee lever 55 is supported for rotatable movement about a horizontal axis by a shaft 59 journaled at either end in suitable support bearings 61 affixed to the base 63 of the machine (see Figure 1).

Also supported upon, and keyed to, the shaft 59 is a second downwardly extending lever 65 which connects at its lower end to one end of a link 67. The other end of the link 67 engages a crank 69 keyed to a vertically extending shaft 71 which is supported upon the base 63 by a suitable bearing 73. A second crank member 75 is keyed to the upper end of the vertical shaft 71, as illustrated particularly in Figures 10 and 11, and this crank 75 operatively connects with the buckle feeding plunger 47 through a short link 77 pivoted at one end to the outer end of the crank 75 and pivoted at its other end to a cross head 79 affixed to the rear end of the plunger 47.

The buckle feeding plunger 47 is biased toward the normal retracted position thereof illustrated in Figures 8, 11, and 17 by two springs 81 each of which is attached at one end to the cross head 79 and at the other end to a suitable stationary pin 83 integrally attached to the bed plate 25 of the machine. A combined stop and guider

member 84 is provided for fixing the limit of rearward motion of the buckle feeding plunger 47 and for preventing displacement of the cross head 79 by the springs 81. This member 84 is I-shaped and the cross head 79 is recessed, as illustrated at 84^a, for engaging the central or guide portion thereof.

The buckle feeding plunger 47 is provided at its outer end with a recess or notch 85 of substantially the same depth as the thickness of the buckles which are to be fed thereby, and the proportions of the apparatus are such that when the plunger 47 is in the normal retracted position this recess 85 will be located immediately beneath the central opening 31 within the magazine. By virtue of this arrangement, forward movement of the plunger 47 will cause the lowermost buckle to be separated from the stack within the magazine and carried forward to the working position.

The buckle is guided in this movement from the magazine to the working position by a guideway 87 formed in the under surface of the magazine base 21 and by a connecting guideway which is defined by two opposed slots 87^a formed in two guide plates 89 and 91 which are mounted on the U-shaped frame 23 of the feeding mechanism. For the purpose of holding each buckle in the working position at the conclusion of each feeding operation, the guide plate 91 is pivotally supported on the frame 23 by a vertical pivot pin 95 and is resiliently biased toward the other guide plate 89 by a suitable loop spring 97 (Figures 11 and 13).

During each buckle feeding operation, the plunger 47 will be moved from its normal retracted position illustrated in Figures 8 and 11 to the feeding position illustrated in Figures 9 and 10 in response to movement of the knee lever 55 from the position illustrated in dotted in Figure 10 to the position illustrated in full in that figure. As explained above, this movement of the buckle feeding plunger 47 will move one of the buckles from the magazine to the working position adjacent the outer end of the guideway formed by the guide slots 87^a, and the resilient support for the guide member 91 assures that the buckle will be held in that working position.

The buckles are placed in the magazine in such manner that the opposed end portions of each buckle will be engaged by the guide slots 87^a and 87^b, as illustrated in Figures 10 and 11, during the feeding operation. At the completion of the feeding operation, the operator will release the knee lever 55, whereupon the spring 81 will automatically retract the feeding plunger and restore the feeding mechanism to its normal position.

The mechanism for opening each buckle after it has been moved to the working position includes a cylindrical plunger 99, which is wedge shaped, at its upper end 100 and which is supported for reciprocating movement along a vertical axis by means of a suitable hollow guide member 101 rigidly affixed to the bed plate 25 by cap screws 103 or the like. The buckle opening plunger 99 is biased downward to the normal or retracted position by means of a compression spring 105, one end of which abuts against the under surface of the guide 101, and the other end of which abuts against a suitable head member 107 keyed to the lower end of the plunger.

A foot treadle 109 is provided for operating the buckle opening mechanism, this treadle being mechanically connected to the plunger 99 by

means of three link members 111, 112, and 113. The link member 112 is pivotally supported on the base 63 by a suitable bracket support illustrated at 115 in Figure 1. The lower end of the link 111 is connected to the treadle 109 through an adjustable collar 117 whereby only counter-clockwise (Figure 1) movement of the treadle 109 will be communicated to the buckle opening mechanism. It is desirable that the apparatus shall include an adjustable stop such as is illustrated at 119 in Figure 1 for determining the lower limit of motion of the buckle opening plunger 99 under the influence of the biasing spring 105.

The proportions and relative positioning of the buckle feeding and buckle opening mechanisms are so correlated that the axis of movement of the buckle opening plunger 99 will intersect the central bar portion of each buckle located in the working position at substantially the mid point of that member. Thus, when the treadle 109 is moved counter-clockwise from the normal position illustrated in Figure 1, the buckle opening plunger 99 will be moved upwardly from its normal retracted position (illustrated in Figures 8 and 9) to the position illustrated in Figures 12 and 13. During this movement, the wedge shaped head 100 of the plunger will open the buckle which has previously been moved to the working position by thereby bending the two halves 110 of the central bar portion of the buckle from the position illustrated in Figure 2 to the position illustrated in Figure 3. The central bar portion of the buckles illustrated in the drawings is severed or scored at the mid portion thereof in order to facilitate the opening thereof. It will be understood, however, that the location of the split or scored portion is to some extent optional, and the apparatus of our invention contemplates the use of other central bar arrangements.

At the conclusion of the buckle opening operation, the buckle is in the state illustrated in Figure 3 and is in position to receive the strap, tape, elastic, or other material to which the buckle is to be applied. A length of this material is looped to form the desired construction, a common form of which is illustrated in Figure 15, and the overlying portions are squeezed together to a form having a cross section similar to an inverted U, as illustrated in Figure 4, and then slipped into the open buckle. When released by the operator, the overlying portion of the elastic or other material will spread out within the buckle and become flat as illustrated in Figure 15. The buckle is then ready to be reclosed.

In order to assure that buckles shall not become displaced during the buckle applying operation, the machine includes a vertically movable latch or stop 114 which is automatically operable to close the outer end of the slots 87a which define the buckle guideway during the applying operation. The latch or stop 114 is positioned within a suitable guide passageway 115 formed in the member 101, and the lower end thereof is threaded for receiving a cylindrical head 117. This head 117 is so positioned, as illustrated in Figure 12, that it will be engaged by the head 107 of the buckle opening plunger 99 during each upward movement of that member, and the latch or stop 114 will thereby be moved automatically from its normal position, illustrated in Figures 1 and 17, to the buckle retaining position of Figures 12 and 14. To prevent the buckle latch 114 from moving downwardly when the buckle open-

ing plunger 99 is restored to its normal position at the conclusion of the buckle opening operation, that member may be provided with friction holding springs 119 which engage suitable slots 5 120 formed in the body portion of the latch.

After each buckle applying operation, it is necessary to reclose the buckle by bending back the central bar portions 11 from the open position of Figures 4 and 15 to the normal closed 10 position of Figure 5. The mechanism for accomplishing the reclosing of the buckle includes a cylindrical plunger 121 supported on the U-shaped frame 41 for reciprocating movement along a vertical axis. The lower end 123 of the buckle closing plunger 121 is preferably wedge shaped, as illustrated in Figure 17, and the upper end of the buckle closing plunger 121 is provided with an adjustable collar 125 for retaining a compression spring 127 which serves to 20 bias the plunger to its normal upward position. The limit of upward movement of the plunger 121 under the influence of this biasing spring is determined by a second adjustable collar 129.

The buckle closing plunger 121 is mechanically connected to the treadle 109 by a tie link 131 and main operating link 133 pivotally supported intermediate its ends on the U-shaped frame 41 by a pivot 135. The main operating link 133 is of bifurcated construction, as illustrated particularly in Figures 7 and 17, in order that it will not interfere with the removal and replacing of the buckle magazine, and the tie link 131 is connected to the treadle 109 through an adjustable collar 137 so located that only clockwise movement 25 (Figure 1) of the treadle 109 will be transmitted to the buckle closing mechanism. The path of movement of the head 123 of the buckle closing plunger 121 preferably intersects the path of movement of the head of the buckle opening plunger 99 at a point coincident with the mid point of the central bar portion of a buckle located in the working position, as illustrated in Figure 16. This assures that proper reclosing of the buckle will follow each operation of the buckle opening mechanism. The collar 129 is provided with an extension 139 which engages the latch or stop 114 during each downward movement of the buckle closing plunger 121, as illustrated in Figure 16, thereby causing the latch 113 to be restored automatically to its normal position following each buckle closing operation.

If the central bar portion of the buckles used in connection with the machine of our invention is provided with serrated edges, as illustrated at 55 140 in Figures 2 and 15, it will usually be found unnecessary to apply a clip to the short end 141 (Figure 15) of the elastic or strap with which the buckle is used for preventing the strap from being drawn through the buckle. The obviating 60 of the use of this clip, which is an essential feature of the prior art arrangements, is an important feature of the present invention, and is believed to result, at least in part, from the positive and accurate opening and reclosing of the buckle 65 which is effected by the machine of our invention.

From the foregoing it will be seen that we have disclosed the features of a new and improved mechanism particularly adapted for applying slide buckles or the like to the straps, tape, or elastic with which such buckles are commonly used. The apparatus of our invention utilizes an improved type of magazine for holding the buckles which are to be so applied, an improved efficient 70 mechanism for feeding these buckles in sequence 75

from the magazine to a working position, novel means for securely holding each buckle moved to the working position throughout the working period, an improved efficient mechanism for opening buckles located in the working position to permit them to be readily applied to the strap or elastic, and an improved efficient mechanism for reclosing each buckle after it has been so applied.

A particularly important feature of the machine of our invention is the mechanical arrangement which automatically returns all of the parts to normal operative position following each operation. The buckle opening plunger 99 and the buckle closing plunger 121 are continuously biased to their respective normal position, and this biasing action is transmitted through the collars 117 and 137 to hold the treadle 109 in its normal intermediate position. Similarly, the means which biases the buckle feeding plunger to its normal retracted position also biases the knee operating lever 55 for the feeding mechanism to the normal position of that mechanism.

It will be apparent to those skilled in the art that various mechanisms may be devised embodying the principles disclosed in the foregoing. Accordingly, it is our desire that the accompanying claims shall be accorded the broadest reasonable construction consistent with the language appearing therein and the prior art.

We claim the following as our invention:

1. In a machine of the class described, a magazine for holding a plurality of buckles, a guideway, means actuatable to move buckles in sequence from said magazine to a working position along said guideway, means for opening buckles located in said working position comprising a reciprocating plunger member, the axis of movement of which intersects the central bar portion of each buckle located in said working position, and means for reclosing buckles opened by said buckle opening means comprising a second reciprocating plunger, the axis of movement of which likewise intersects the central bar portion of buckles held in said working position.

2. In a machine of the class described, a magazine for holding a plurality of buckles, a guideway, means actuatable to move buckles in sequence from said magazine to a working position along said guideway, resilient means for releasably holding each buckle moved to said working position, means for opening buckles located in said working position comprising a reciprocating plunger member, the axis of movement of which intersects the central bar portion of each buckle located in said working position, and means for reclosing buckles opened by said buckle opening means comprising a second reciprocating plunger, the axis of movement of which likewise intersects the central bar portion of buckles held in said working position.

3. In a machine of the class described, a magazine for holding a plurality of buckles, means actuatable to move buckles in sequence from said magazine to a working position spaced some distance from said magazine, an operating member movable from a normal intermediate position to either of two extreme positions, means actuatable in response to movement of said operating member from said intermediate position to one extreme position to open a buckle located in said working position by bending the central bar portion thereof, and means actuatable in response to movement of said operating member from said intermediate position to said other extreme posi-

tion to close said buckle by restoring said central bar portion to a normal closed position.

4. In a machine of the class described, a magazine for holding a plurality of buckles, a guideway, means actuatable to move buckles in sequence from said magazine to a working position along said guideway, means for releasably holding each buckle so moved in said working position, an operating member movable from a normal intermediate position to either of two extreme positions, means including a reciprocating plunger actuatable in response to movement of said operating member from said intermediate position to open a buckle located in said working position by bending the central bar portion thereof, and means including a second reciprocating plunger actuatable in response to movement of said operating member from said intermediate position to said other extreme position to close said buckle by restoring said central bar portion to a normal closed position.

5. In a machine of the class described, a magazine for holding a plurality of buckles, means actuatable to move buckles in sequence from said magazine to a working position, means for releasably holding each buckle so moved in said working position, means for opening buckles located in said working position comprising a reciprocating plunger member, the axis of movement of which intersects the central bar portion of each buckle located in said working position, means for reclosing buckles opened by said buckle opening means comprising a second reciprocating plunger, the axis of movement of which likewise intersects the central bar portion of buckles held in said working position, and a common actuating means for said buckle opening and said buckle closing means comprising a treadle movable from a normal intermediate position to one extreme position to operate said buckle opening means and from said intermediate position to an opposite extreme position to operate said buckle closing means.

6. In a machine of the class described, a magazine for holding a plurality of buckles, a guideway, means for moving buckles in sequence from said magazine to a working position along said guideway, a knee lever movable from a normal inoperative position to an operative position to actuate said buckle moving means, means for opening buckles located in said working position comprising a reciprocating plunger member, the axis of movement of which intersects the central bar portion of each buckle located in said working position, means for reclosing buckles opened by said buckle opening means comprising a second reciprocating plunger, the axis of movement of which likewise intersects the central bar portion of each buckle held in said working position, and a common actuating means for said buckle opening and said buckle closing means comprising a treadle movable from a normal intermediate position to one extreme position to operate said buckle opening means and from said intermediate position to an opposite extreme position to operate said buckle closing means.

7. In a machine of the class described, a magazine for holding a plurality of buckles, a guideway, means actuatable to move buckles in sequence from said magazine to a working position along said guideway, means comprising a reciprocating plunger actuatable to open a buckle located in said working position by bending the central bar portion thereof, latch means actuatable in response to movement of said buckle opening plunger to

positively latch said open buckle against movement out of said working position, and means comprising a second reciprocating plunger actuatable to close said buckle and to release said latch means.

8. In a machine of the class described, a magazine for containing a plurality of slide buckles, a guideway, means actuatable to move individual buckles in sequence from said magazine to a working position along said guideway, means including a reciprocating plunger movable from a normal retracted position to an extended position to open a buckle located in said working po-

10 sition by bending the central bar portion thereof, latch means movable in response to movement of said buckle opening plunger from said normal position to said extended position to close the outer end of said guideway and thereby prevent withdrawal of said open buckle from said guideway, and means including a second reciprocating plunger movable from a normal retracted position to an extended position to close buckles held in said working position and to move said latch means away from the end of said guideway.

KENNETH J. HARWOOD.
GEORGE E. KLOCK.
